MACHINE FOR APPLYING PINS IN FITTING GARMENTS

Thomas A. Benton, Cincinnati, Ohio

Application January 18, 1937, Serial No. 121,097

6 Claims. (CL. 33—9)

My invention relates to a novel machine for applying pins to garments and has particular adaptation in the application of pins during fitting to indicate the line where a hem is subsequently to be made.

Practically all ready to wear garments, particularly ladies and misses, have an open hem at the bottom. The fitter, usually in a semi-recumbent position on the floor, either measures with a tape and applies a series of chalk marks or by carrying a supply of pins, inserts a pin to indicate the desired hem line. The labor involved both to the fitter and the person being fitted is tedious and movement of the body disarranges the hang of the garment, so that often hems have to be changed after they are pinned up. The setting of the hem further requires the person being fitted to go through a tiresome period of standing and waiting for the final adjustment of the garment.

It is the object of my invention to provide a machine which will mechanically insert a series of pins in a garment a predetermined distance from the floor line without the tedious waiting on the part of the person being fitted and the uncomfortable crouching and manual insertion of the pins by the fitter.

There is a machine on the market for making chalk marks, to indicate the hem line, which operates on somewhat the same principle as my machine, but since most accurate fitting is done with pins and since the chalk marking machine is not adapted to insert pins, the novelty of my apparatus will be apparent.

35 Referring to the drawing:

Figure 1 is a perspective view on a small scale showing my machine in use.

Fig. 2 is a side elevation of the machine with parts broken away and certain parts shown in section.

Fig. 3 is a horizontal section along the lines 3—3 in Fig. 2.

Fig. 4 is a horizontal section along the lines 4—4 in Fig. 2.

45 Fig. 5 is a horizontal sectional view with the parts shown in Fig. 4 in pin inserting position.

Fig. 6 is a sectional view along the lines 6—6 in Fig. 4.

The machine is formed on a base 1, which is sufficiently weighted or otherwise prepared to stand on the floor without tipping over. An upright bar 2, preferably provided with measurement indicia 3, and set at a slight angle as indicated, carries a slider member 4 which may be positioned as desired on the bar 2 by means of

the thumb screw 5. The slider member 4 has a beveled slot 6 for receiving the spring 6a of the pin hammer member to be described, and roughened surfaces 7 to assist in sufficient holding of the garment to permit the pin hammer to operate.

Spaced on the base from the bar 2, I provide a vertical bearing member 8 having an arcuate slot 9 therein. A bar 10 rotatable on a vertical axis, has a rounded end 11 mounted in the bearing and 10 a pin 12 limits the rotary swiveling of the bar 10, by contact with the bumper members 12a and 12b. A gear 13 is mounted on the bar 10 and the teeth of the gear 13 mesh with a half round gear 14.

The half round gear is mounted on a fixed shaft 15. A hub 16 is rotatably mounted on the shaft 15 and an angle bar 17 is fixedly attached to the hub 16. The angle bar carries a pawl 18 resiliently held by the spring 19. The other end 20 of the spring 19 is secured to the hub 16. A spring 21, secured to the post 20 is secured to the pinion 13 to assist in the operation of tripping the pawl 18. Another spring 17a is also secured to the post 20 and is fixed at its other end to the pin 17b upstanding from the angle bar 17. This spring 17a urges the angle bar and handle 26 to the position shown in Fig. 3. Pin 17b also serves as the pivotal mounting for the pawl 18.

The pawl carries an abutment in the form of a 30 vertically pivoted roller 22 which during operation of the pin inserting mechanism is brought into engagement with a member 23 which, in the embodiment of the invention illustrated, comprises a spring 24 mounted on a post 25.

A handle 26, secured to the angle bar 17 provides the means for actuating the pin inserting mechanism by operation in a counter clockwise direction as illustrated. An abutment or bumper member 26a serves to limit undue movement of 40 the handle 26.

The bar 10 is graduated as indicated at 27 and carries the pin hammer 28 adjustably mounted by means of a thumb nut 29.

The pin hammer has a nose 30 and a pair of 45 pin carrying jaws 31, 32, the upper jaw 32 being resiliently mounted and pressed down by a spring 33 attached to a post 34.

The head of a pin is inserted in the space 35 with the shaft of the pin retained between the 50 jaws 31, 32.

When the handle 26 is moved counterclockwise the pawl bears against an eccentric segment 36 formed on the half round gear 14 and the gear 13 is thereby rotated through an arc of about 90°. 55

At the limit of this movement the vertically pivoted roller 22 engages the abutment 23 and the pawl 18 is tripped counterclockwise permitting the mechanism to return to starting position.

5 During the operation of the mechanism the pin is carried by the pin hammer from the starting position shown in Fig. 4 to the pin inserting position shown in Fig. 5.

At the instant when the spring 8a bears in the 10 slot 6 and temporarily holds the garment into which the pin is to be inserted, the pawl is tripped and the pin hammer swings counterclockwise. The end of the pin penetrates the brush 37 and since the garment is retained in vertically folded 15 position the pin penetrates only the fold thereby mechanically inserting the pin in substantially the same way that a fitter would insert it.

In the mechanical arrangement illustrated, I have but used mechanical parts of known structure and operation and modifications will readily occur to those skilled in the art. As far as I am advised my apparatus and the method of use represents the first solution of the problem of mechanically setting the hem line in a garment 25 being fitted, thereby replacing the manual manipulations of a fitter.

Having thus described my invention, what I claim as new and desire to secure by Letters Patent is:

30 1. A device for use in fitting garments, comprising vertically adjustable fold producing means, other vertically adjustable means for releasably carrying a pin, means for oscillating said pin carrying means in one direction, and means operative after predetermined degree of oscillation of said pin carrying means for rapidly oscillating said pin carrying means in a reverse direction whereby a pin held in said pin carrying means is thrust through a fold produced by said fold producing means.

40 2. A device for use in fitting garments, comprising vertically adjustable fold producing means, other vertically adjustable means for releasably carrying a pin, means for oscillating said pin carrying means in one direction, and means operative after a predetermined degree of oscillation of said pin carrying means for rapidly oscillating said pin carrying means in a reverse direction, whereby a pin held in said pin carrying 45 means is thrust through a fold produced by said

fold producing means, said last mentioned means being resilient and permeable, and said pin passing through said means.

3. A device for use in fitting garments, comprising a vertically adjustable fold producing means, other vertically adjustable means for releasably carrying a pin, said other means carrying also a resiliently mounted fold member, means for oscillating said pin carrying means in one direction at least until said fold member bears 10 against said first mentioned means, whereby a fold is produced, and means operative when said fold has thus been produced for rapidly oscillating said pin carrying means in a reverse direction, whereby a pin held in said pin carrying 15 means is thrust through said fold.

4. A device for use in fitting garments, comprising a vertically adjustable fold producing means, said means being resilient and permeable, other vertically adjustable means for releasably 20 carrying a pin, said other means carrying also a resiliently mounted fold member, means for oscillating said pin carrying means in one direction at least until said fold member bears against said first mentioned means, whereby a 25 fold is produced, and means operative when said fold has been thus produced for rapidly oscillating said pin carrying means in a reverse direction, whereby a pin held in said pin carrying means is thrust through said fold and said first 30 mentioned means.

5. A device for use in fitting garments, comprising a member about which a fold may be produced, said member comprising a brush, means cooperating with said member for producing a fold, and means operative when said fold has been formed, for thrusting a pin therethrough, said pin passing also through said member.

6. A device for use in fitting garments, comprising a member about which a fold may be produced, said member being resilient and permeable and having a rough surface, means cooperating with said member and said surface for producing and holding a fold, and means operative while said fold is being held, for thrusting a pin therethrough, said pin passing also through said member.
